(Cl. D52—2)

To all whom it may concern:

Be it known that we, Charles M. Stern and Gustave C. Cattani, citizens of the United States, residing in the city and county of San Francisco, State of California, have invented a new, original, and ornamental Design for a Dispenser for Olives, Cherries, Small Onions, and the like, of which the following is a specification, reference being had to the accompanying drawing, forming part thereof.

Figure 1 is a top view of a dispenser for olives, cherries, small onions, and the like, showing our new design;

We claim:

The ornamental design for a dispenser for olives, cherries, small onions, and the like, as shown.

CHARLES M. STERN.
GUSTAVE C. CATTANI.
